UNITED STATES PATENT OFFICE.

FRANK H. CHAPMAN AND OWEN E. KENNEY, OF TOLEDO, OHIO, ASSIGNEES TO THE YOST ELECTRIC MANUFACTURING COMPANY, OF TOLEDO, OHIO, A CORPORATION OF OHIO.

DESIGN FOR AN ATTACHMENT-PLUG FOR ELECTRIC CIRCUITS.

44,704.

Specification for Design.

Patented Sept. 30, 1913.

Continuation of application Serial No. 756,023, filed March 21, 1913. This application filed August 6, 1913. Serial No. 783,418. Term of patent 14 years.

To all whom it may concern:

Be it known that we, FRANK H. CHAPMAN and OWEN E. KENNEY, citizens of the United States, residing at Toledo, in the county of Lucas and State of Ohio, have invented a new, original, and ornamental Design for an Attachment-Plug for Electric Circuits, of which the following is a specification, reference being had to the accompanying drawings, forming part thereof.

In the drawings, Figure 1 is a side elevation, and Fig. 2 an outer end elevation of an attachment plug for electric circuits showing our new design.

This application is filed as a continuation of the application filed by us March 21, 1913, Serial No. 756,023, said application having been abandoned in favor of the present one.

We claim:

The ornamental design for an attachment plug for electric circuits, as shown.

FRANK H. CHAPMAN.
OWEN E. KENNEY.
